UNITED STATES PATENT OFFICE

2,409,351

STITCH PICKER

Ishmael H. Gearhart, Salem, Va.

Application January 24, 1946, Serial No. 643,143

3 Claims. (Cl. 12—17)

1

The invention relates to a device for removing switches from shoe welts which may be connected to suitable parts of a shoe or other footwear and more especially to a stitch picking device.

The primary object of the invention is the provision of a device of this character, wherein the stitches connecting parts of a shoe or the like together will be withdrawn so that these parts, when separated, cleared of the severed stitches without the use of a hand knife or other similar cutter, as is commonly used in shoe repair shops.

Another object of the invention is the provision of a device of this character, wherein through the rotation of a disk or other rotor, the picking protuberances being disposed thereon in a manner, will positively draw the threads in switch formation, so that the parts of a shoe to be clean thereof either before or after separation of the parts and this is effected with ease and dispatch.

Another object of the invention is the provision of a device of this character, wherein the severing of the stitches, the latter will be drawn out of the material and picked from a shoe automatically, thereby relieving hand activity for this purpose through the use of a hand tool.

A further object of the invention is the provision of a device of this character, which is simple in construction, thoroughly reliable and efficient in operation, strong, durable, power driven, readily and easily applied in position and removed, constructed for convenient handling and inexpensive to manufacture and install.

With these and other objects in view, the invention consists in the features of construction, combination and arrangement of parts as will be hereinafter more fully described, illustrated in the accompanying drawings, which show the preferred and modified forms of construction thereof, and pointed out in the claims hereunto appended.

In the accompanying drawings:

Figure 1 is an outside face view of the device constructed in accordance with the invention.

Figure 2 is a sectional view taken on the line 2—2 of Figure 1 looking in the direction of the arrows.

Figure 3 is a plan view of the hub area of the device, looking toward the rear end thereof.

Figure 4 is a similar view looking toward its front.

Figure 5 is a fragmentary elevation of the picker disk.

Figure 6 is an end view of the arbor.

2

Figure 7 is a sectional view through the structure shown in Figure 5.

Figure 8 is a view similar to Figure 2 showing a modification.

5 Figure 9 is a view similar to Figure 1 showing the modified form in Figure 8.

Figure 10 is a diagrammatic flattened view of the rim area of the modified form in Figure 8.

10 Figure 11 is a view similar to Figure 8 showing a further modification.

Figure 12 is a plan view thereof.

Similar reference characters indicate corresponding parts throughout the several views in the drawings.

15 Referring to the drawings in detail, the device constituting the present invention is very compact, and comprises essentially a flat substantially circular ring-like work engaging member 10, having a center clearance for accommodating an annular shoulder 11, providing a seat 12 concentric thereto countersunk in a sleeve-like hub 13, which is adapted to be keyed or otherwise made fast on the reduced terminal 14 of a rotating arbor 15, only a portion thereof being

20 shown in Figures 1, 2 and 3 of the drawings. The terminal 14 is formed with a key lug 16, which is engaged in a spiral way 17, provided in the clearance in the hub for such terminal, and the said hub is formed with an entrance throat 18 for the lug 16, so that in this manner the hub can be detachably secured fast on the arbor.

25 The member 10 concentrically of the center clearance in the hub 13 for the arbor terminal 14 has cut and struck outwardly grouped series

30 of spaced picker teeth, each group involving three substantially half-circular shaped outwardly arched or concave-convexed built protuberances 18, 19 and 20 respectively, each constituting a tooth, and the protuberance 18 is set radially to the axis of such member, while the protuberances 19 and 20 are disposed at reverse angles to each other and to the protuberance 18, as best seen in Figures 1 and 5 of the drawings.

35 The member 10 is held fast in the seating thereof on the hub 13 by a spline 21, which is clearly shown in Figures 1 and 4 of the drawings, yet the said member may be otherwise secured on the hub. The angle of the protuberances 19 and 20 is approximately 45 degrees to the position of the protuberance 18.

40 In Figures 8 to 10 inclusive, of the drawings, there is shown a modification of the invention, wherein there is provided a substantially cupped or flared ring-member 22, forming a rim 23, 45 with a shoulder 24, the latter seated at 25 on the

50 55

hub 26 and this rim 23 has cut and struck therefrom the outwardly disposed teeth 27, 28 and 29 respectively, grouped and built identically to the protuberances 18, 19 and 20 hereinbefore described.

In Figures 11 and 12 of the drawings, there is shown a further modification of the invention, wherein the hub 30 has integrally formed therewith the rim 31 over which is telescoped the member 32 each tooth thereof being denoted at 33.

In the use of the device, the shoe to be worked upon is positioned as best seen in Figure 2 of the drawings, with the welt 34 exposed to the path of the protuberances constituting the teeth and in the rotation of the device, the threads will be removed from the welt and the sole 35 of the shoe for the clearing of such threads or stitches therefrom as should be clearly obvious, the teeth being active on the switches in three distinct directions in a circular course on the rotation of the said device.

What is claimed is:

1. A device of the kind described, comprising a rotary arbor, and a circular member fixed to the arbor and having a work engaging periphery provided with grouped series of spaced protuber-

ances, each of one group being of substantially half-circular outwardly arched formation, the protuberance of one group being disposed radially of the axis of the arbor and the others of said group being reversely angled thereto.

2. A device of the kind described, comprising a rotary arbor, and a circular member fixed to the arbor and having a work engaging periphery provided with grouped series of spaced protuberances, each of one group being of substantially half-circular outwardly arched formation, the protuberance of one group being disposed radially of the axis of the arbor and the others of said group being reversely angled thereto and means for fast seating the member on the arbor.

3. A device of the kind described, comprising a rotary arbor, and a circular member fixed to the arbor and having a work engaging periphery provided with grouped series of spaced protuberances, each of one group being of substantially half-circular outwardly arched formation, the protuberance of one group being disposed radially of the axis of the arbor and the others of said group being reversely angled thereto and a hub interfitting the member and arbor respectively.

ISHMAEL H. GEARHART.
